UNITED STATES PATENT OFFICE

1,975,618

CATAMENIAL BANDAGE RETAINERS

Hyman Raskin, Chicago, Ill.

Application January 13, 1933, Serial No. 651,471

3 Claims. (Cl. 128—290)

My invention relates to improvements in catamenial bandage retainers, and has for an object the provision of a device which is adapted to retain sanitary napkins and protect clothing of a wearer from becoming soiled because of soaking through of the discharge. The device is adapted to retain the napkin in proper position, and it is well adapted for use with the widely advertised napkins which are on the market.

10. Another object is the provision of a device which, due to its peculiar characteristics, will tend to conform to the shape of the parts to which the device is applied when any tension is applied to the attaching strips. The shape, character of material, and arrangement of parts of the device assist in achieving this object.

My device is simple in construction, long wearing, easy to sterilize, and it is so arranged that soiled napkins may be easily removed from the 20. device without soiling the fingers.

The character of materials is such that they may be obtained very cheaply, and my construction is relatively simple so that manufacturing costs are slight.

25. The preferred embodiment of my invention may be best understood by reference to the accompanying drawing, in which:

Fig. 1 is a bottom plan view;

Fig. 2 is a side elevational view;

30. Fig. 3 is a top plan view, with the usual sanitary napkin inserted in the device;

Fig. 4 is a sectional view, taken substantially on the line 4—4 of Fig. 2, and also illustrates a napkin in place;

35. Fig. 5 is a detail view illustrating my convenient napkin securing arrangement; and

Fig. 6 is a detail view showing how the material forming the main body portion of my device is cut and arranged before it is finally put 40. together and secured in place.

As can be seen from Fig. 2, my device comprises a bottom portion 10 having secured thereto side portions 11 which may be attached by stitches 12. The side portions and bottom portion may be made of a very thin grade of rubber now commonly called latex. The unsecured edges of side portions 11 may be bound by bias tape 13, and the ends of side portions 11 and bottom portion 10 may be bound by bias tape 14 which may overlap in securing a napkin and be held together by clasp 15 on stud 16, or the two free ends of tape 14 may be sewn together. This overlapping provides a loop for the napkin end.

When tape 14 is being attached to portions 45. 11 and portion 10, attaching tapes 17 may have

their ends inserted between the folded edges of tape 14 and be stitched to tape 14 and portion 10 at the same time the remainder of the stitching on tape 14 is done. The usual form of sanitary napkin 18 is provided with extending attaching strips which may pass through the overlapping and clasped ends of tape 14 and be superposed on strips 17. The two thicknesses may then be pinned to the usual catamenial belt. It 60. can be seen of course that this arrangement provides an extremely secure support for napkin 18.

From an inspection of Fig. 2 it can be seen that portion 10 curves upwardly longitudinally from point 19 and curves upwardly transversely from the center, as at points 20, the latter 70. curve being shown particularly well in Fig. 4. Side portions 11 may curve inwardly toward the center of the device from the points 21, and of course assist materially in securing napkin 18 75.

An inspection of Fig. 6 discloses how the bottom and side portions may be cut from the same piece of material, since the curves of their edges are concentric, as shown by curved lines 22 and dotted lines 24. When the material is cut along 80. line 22 the outer edges of portion 10 are formed and the inner edges of portions 11 are formed along the same line. However, when the strips are put together the side portions 11 are turned over and assume the position shown in full lines 85. in Fig. 6, and then the inner edges become the outer edges 23. Edges 22 and 24 are then overlapped slightly and may be secured by stitching. It can be seen that this arrangement and construction will cause the side strips and bottom 90. strips to assume a shape substantially similar to that of a canoe, and will form an excellent pocket for the napkin. It is also apparent that when the retainer is applied to the person of the user and placed in the bent position which it assumes, any tension on strips 17 will be transmitted through binding 14 to binding 13 and cause the sides to be drawn up more snugly and not buckle as they would if my construction were 95. different. One advantage of course is apparent in that a deeper basin or cavity is formed for the retention of any excess discharge, and another advantage is that the side strips 11 and binding 13 will not spread and chafe the inner limbs of the wearer, since they are pulled toward each other and do not buckle.

100. It is apparent that bottom portion 10 and side portions 11 could be made of the same configuration and shape by known processes in one piece 105. 110.

of latex instead of making them from separate strips as I have indicated here.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

15. 1. A device of the character described comprising a napkin receiving member having upstanding side portions, a bottom portion, and bias tape binding strips secured to the upper edges of said upstanding side portions and bias tape binding strips secured to the end of said upstanding side portions and bottom portion.

20. 2. A device of the character described comprising a napkin receiving member having a bottom portion whose longitudinal edges are convex in plan outline, upstanding side portions having

convex longitudinal edges, said last mentioned convex edges being secured to said convex edges of said bottom portion, binding strips secured to the upper edges of said upstanding side portions, binding strips secured to the ends of said bottom portion and said upstanding side portions, and attaching strips secured to said last mentioned binding strips, said last mentioned binding strips being adapted to form napkin end retaining loops.

80
85

3. A device of the character described comprising a napkin receiving member having a bottom portion whose longitudinal edges are convex in plan outline, upstanding side portions having convex longitudinal edges, said last mentioned convex edges being secured to said convex edges of said bottom portion, bias tape binding strips secured to the upper edges of said upstanding side portions, bias tape binding strips secured to the ends of said bottom portion and said upstanding side portions, and attaching strips secured to said last mentioned bias tape binding strips, said last mentioned bias tape binding strips being adapted to form napkin end retaining loops.
